UNITED STATES PATENT OFFICE.

MARCUS O. ANTHONY, OF NEW YORK, N. Y., ASSIGNOR TO A. KIMBALL COMPANY, OF NEW YORK, N. Y., A CORPORATION OF NEW YORK.

TAG-SEWING MACHINE.

1,143,929.

Specification of Letters Patent. Patented June 22, 1915.

Application filed September 3, 1913. Serial No. 788,025.

To all whom it may concern:

Be it known that I, MARCUS O. ANTHONY, citizen of the United States, residing at New York, county of New York, State of New York, have invented an Improvement in Tag-Sewing Machines, of which the following description, in connection with the accompanying drawing, is a specification, like characters on the drawing representing like parts.

This invention has reference to sewing machines, and more particularly to an automatic machine for sewing tickets upon merchandise.

Various forms of tickets are extensively used for marking merchandise to indicate the size, quality, price, etc. The sewed ticket offers several advantages over other forms, among which are the possibility of applying to fine goods without damaging the goods, the absence of metal which may rust and stain the goods, the absence of projecting metal points to prick the fingers or catch in other goods, and the permanence of the attachment making it difficult for dishonest clerks or purchasers to change tickets. The needle being sharp and smooth penetrates even fine fabrics without damage such as is caused by the roughly finished points of machine made pin tickets. One of the requirements of tickets for marking merchandise is that goods may be quickly marked as for example when a large quantity of new goods are to be offered for sale or when goods are to be re-marked as for a clearance sale.

The main object of the invention is accordingly to provide a machine for sewing tickets upon merchandise which will quickly and automatically perform the various operations necessary, such as clamping and releasing the work, sewing the ticket to the merchandise and stopping the operation of the stitch forming mechanism after a predetermined number of stitches, securing the thread so that it will not unravel, cutting the thread, and restoring the parts to initial position.

Other objects will appear from the following specification and the accompanying drawings in which the novel features will be fully disclosed and particularly pointed out in the claims.

Referring to the drawings, in which I have illustrated a preferred embodiment of my invention, Figure 1 is a side view of an automatic machine constructed in accord-

ance with my invention. Fig. 2 is a front view of the same. Fig. 3 is a plan view partly in section taken on the line 3—3, Fig. 1. Fig. 4 is a detail of a ratchet mechanism which operates in conjunction with the carriage feed. Fig. 5 is a bottom plan view showing the feed rack and thread cutting mechanism. Fig. 6 is a view partly in section taken on the line 6—6, Fig. 1. Fig. 7 is a sectional view taken on the line 7—7 Fig. 6. Fig. 8 is a detail view of the clutch pin. Fig. 9 is a perspective view of the movable rack segment. Fig. 10 is a detail view of the clamp releasing mechanism and Fig. 11 is a sectional view showing the rack segment detent and the releasing cam therefor.

The mechanism illustrated comprises a support, a carriage pivotally mounted for a limited swinging movement upon said support, stitch forming mechanism mounted upon said carriage, a feed mechanism to impart a swinging movement to said carriage during the sewing operation and means for returning the carriage to initial position, a work clamp, thread cutting mechanism for cutting the thread at the end of the sewing operation, an adjustable mechanism to vary the length of the line of stitching, a motor, and a clutch for connecting the motor to the stitch forming mechanism.

Referring to the drawings in detail the support comprises a base plate 1, a platform 2, a work table 3, and several distance members 4 and 5, connecting the same. Upon the base plate 1, I mount a motor 6, and connect this to the main drive shaft 7, by means of a grooved pulley 8, secured to the motor shaft, a grooved pulley 9, mounted on the main shaft and connected thereto by a clutch 10, and a coil spring belt 11, connecting the pulleys. Elongated holes 12 and 13, in the platform permit the passage of the belt during the swinging movement of the carriage 14.

The carriage is made in two parts, a lower or body portion 15, and a cover plate 16. A screw bolt 17, extends through a hole 18, in the body portion and is secured in the platform thus pivotally connecting the carriage to the platform as shown in Fig. 6. The opposite end of the carriage is formed on an arc having its center at the pivotal point and is grooved as shown at 19. A correspondingly curved guide 20, is secured to the platform 2, adjacent this end of the car-

riage and is provided with a rib 21, having ratchet teeth 22, the rib thus acting as a guide for the end of the carriage and as the rack of a ratchet mechanism to be herein-after described.

5 The stitch forming mechanism comprises a frame 23, secured to the carriage 14, the main shaft 7, a needle bar 24, a needle bar oscillator 25, all mounted in the frame, an eccentric 26, secured to the main shaft, a connecting rod 27, connecting the eccentric 26, to the needle bar oscillator 25, a looper 28, secured to the end of the main shaft 7, and a tension device 29, arranged to be operated from the eccentric 26, by the lever 30, pivoted to the frame at 31, and the rod 32, slidably mounted in the frame. The stitch-forming mechanism operates at a sufficient distance from the pivot of the carriage so that the line of stitching will extend in a substantially straight line across the ticket. As this stitch forming mechanism in itself is of common and well known construction it will not be described more in detail. I have illustrated and prefer to use a stitch forming mechanism of the single thread type, as this is simpler and better adapted to this class of work.

10 The feed mechanism for swinging the carriage 14, about its pivot comprises a rack 33, secured to the underside of the work table 3, as by screws 34, and a pawl 35, mounted on an eccentric 36, and having a wide tooth 37, for engaging the rack 33. 15 This pawl 35, is so arranged that during each revolution of the main shaft, and while the needle bar is in elevated position, it will engage the rack 33, and swing the stitch forming mechanism about its pivot 17, a distance determined by the length of the teeth on the rack 33, and the eccentricity of the eccentric 36.

20 A spring drum 38, secured to the platform 2 and connected to the carriage 14, by the cord 39, tends always to return the carriage to initial position and a ratchet mechanism 40, holds the carriage in position after each feeding movement. This ratchet mechanism comprises the rack 21, previously mentioned and a pawl 41, slidably mounted in a groove 42, in the body member 15, of the carriage and pressed forward by a spring 43. A cam 44, is positioned at the end of the rack 21, or made integral therewith as shown in Fig. 4 so that when the pawl 41, is engaged by this cam during the last feeding movement of the carriage the pawl will be moved back a greater distance than when moving over the teeth 22, of the rack. A 25 pivotally mounted retaining latch 45, is urged toward the pawl 41, by a spring 46, and when the pawl is given this extreme movement by the cam 44, the latch 45, engages a notch 47, in the pawl and holds the 30 pawl in this inoperative position. As the

pawl 35, moves down after the last feeding movement the spring drum 38, will swing the carriage 14, and the mechanism mounted thereon back to its initial position. The initial position is determined by the adjustable stop 48, which comprises a slotted plate having a tooth 49, which may be adjusted to engage any one of the teeth of a toothed segment 50, secured to the platform 2. The stop 48, is held in adjusted position by the thumb screw 51. When the carriage 14, swings back to the initial position the pin 52, engages the stop 48, and swings the pawl 45, about its pivot releasing the pawl 41, and permitting it to engage the rack 21. By this mechanism the carriage is given a feeding movement step by step for the full distance of its travel and is automatically restored to initial position.

35 The thread may be fastened at the end of the row of stitches to prevent unraveling as for example by drawing the end of the thread through the last loop or by tying a knot in the thread. I prefer to tie a knot in the thread and for this purpose I provide a mechanism whereby the last two stitches are made in the same hole. To accomplish this I provide a rack segment 53, having two teeth 54 and 55, slidably mounted at the end of the rack 33 as by screws 56 and 57, extending through a slot 58, and secured in the table 3. The segment 53 is slotted as shown at 59 to receive the end 60, of the rack 33, and it is mounted to permit a movement equal to the distance between two successive teeth. The screw 56 engages the end of the slot 58, to limit the movement of the segment in one direction and the end 60 of the rack 33, engages the segment at the end of the slot 59, to limit movement in the opposite direction. A spring 61, urges this segment away from the rack. As will be noticed the tooth 54, of the segment is positioned laterally of the rack 33, and the tooth 37, of the pawl 35, is made sufficiently wide to engage this tooth as well as the rack teeth. A spring detent 62, having a projection or catch 63, is secured to the segment and a recess 64, is provided in the underside of the work table in position to be engaged by the catch when the segment is in the position nearer the rack. When the pawl tooth 37 engages the tooth 54 of the segment the spring 61 will yield and the segment will move toward the rack and be retained there by the detent 62, thus permitting the carriage to remain in the same position for a second stitch. Upon the next rotation of the main shaft the pawl tooth 37, will engage the tooth 55, of the segment and move the carriage one step forward. During this last feeding movement the thread cutting mechanism, the clutch releasing mechanism, and the previously described mechanism for withdrawing the pawl 41, 130

will be operated and the carriage will return to initial position.

The detent 62, is provided with a lateral projection 65, and a cam 66, carried by the frame of the stitch forming mechanism will engage this projection 65, during the return movement of the carriage, moving the catch 62, out of the recess 64, and permitting the segment 53, to return to its initial position under the operation of the spring 61. The position of the cam 66 on the frame 23 is substantially above one of the bearings of the shaft 7 as indicated in Fig. 3. This cam passes above and depresses the projection 65, both on the return movement and on the forward or feeding movement of the carriage and if for any reason the segment 53, fails to move back to initial position upon the first engagement it will so move upon the second engagement of the cam with the projection 65, as the carriage moves forward during the stitch forming operation, the more certainly so because the pressure of the beveled surface 67, of the cam on the projection 65 is operating in such a direction at this time as to assist the movement of the segment 53 to initial position. This simple expedient of forming 2 stitches in the same hole ties a knot which securely prevents the accidental unraveling of the thread while at the same time permitting easy removal of the tag by cutting the knot.

The thread cutting mechanism is shown in Figs. 2, 3, and 5. This mechanism comprises a knife blade 68, slidably mounted in a guide 69, secured to the underside of the worktable 3. A pin 70, projects from the blade and engages in a slot 71, in a lever 72, pivoted at 73. I have shown this lever as mounted on a plate 74, which in turn is secured to the work table 3, and which is provided with a stop pin 75, to limit the movement of the lever. A spring 76, is arranged to return the lever to initial position after the cutting operation. A pawl 77, is pivoted in a bracket 78, and is normally urged toward the lever 72, by a spring 79. As the carriage swings about its pivot during the stitch forming operation a spring pressed plunger 80, carried by the carriage engages the lever 72, at 81. This plunger 80, is urged forward by a spring 82, which is considerably stronger than the spring 76. As this plunger 80, engages the lever 72, the spring 82, is compressed, the lever 72 being held against movement by the pawl 77. As the carriage approaches the end of its travel the pawl is depressed by a pin 83, engaging the cam surface 84, of the said pawl 77, and the knife is given a quick forward movement. The length of the pin 83 is such that the lever is released during the last feeding movement of the carriage and before its return to initial position. The thread is thus cut immediately after the knot is tied. The

knife 68, is so shaped that it will engage the thread at an angle and therefore be more certain to sever it. As the carriage returns to initial position the spring 76, will move the lever back in position to be again engaged by the pawl 77.

The work clamping mechanism comprises a clamping member 85, between which and the work table the work is held during the sewing operation. This clamping member is pivoted as at 86, to a bracket 87, secured to the work table. A second bracket 88, is secured to the work table as shown in Figs. 1, and 5, and is provided with projections 89 and 90 extending above the plane of the table behind the bracket 87. Springs 91 and 92 are secured to these projections and to the ends of a bar 93 secured to the work clamping member. These springs are so positioned that when the clamp is down the springs will lie in a plane below the pivotal point 86, and when the clamping member is in elevated position the springs will extend above this pivot 86. In this manner the springs tend to retain the clamp either in its elevated position or in its depressed or clamping position. This clamping member is provided with an extension 94, extending toward the frame of the stitch forming mechanism. A cam 95, is pivoted to the frame 23, at 96, as shown in Fig. 1 and the pivotal movement of this cam is limited by a stop 97. As the carriage returns to initial position after the sewing operation the face 98 of this cam will engage the projection 94, of the clamping member and depress it to raise the clamping member and release the work. During the feeding movement however the face 99, of the cam will engage the projection and the cam will swing about its pivot thus not affecting the position of the clamping member. Slots 100 and 101 in the clamping member and work table respectively permit the passing of the needle, the slot in the clamping member being sufficiently wide to permit its movement on the pivot 86 without binding on the needle. The work clamping member is automatically pressed down to clamp the work by the first downward movement of the needle bar 21, is retained in this position by the springs 91 and 92. By this mechanism the clamping member is automatically operated to clamp the work at the very beginning of the stitch forming operation and to release it at the end of such operation.

The term "work clamp" as found in the claims is used in a broad sense to designate means for gripping the work, but is not limited to means approaching the work from opposite sides to grip it therebetween as shown in the embodiment illustrated in which the work is clamped between the work table 3 and the clamping member 85, co-operating therewith to grip the work.

The clutch which connects the pulley 9 to the main shaft may be of any suitable type but is preferably of such a design that it will be disconnected at a definite point of the 5 revolution of the main shaft thus, always stopping the stitch forming mechanism when the needle bar is in elevated position. In the construction illustrated, disks 102 and 103 are mounted on the shaft 7 on opposite sides 10 of the pulley 9 and secured by setscrews. A hole is drilled half in the shaft and half in the pulley and disks thus forming grooves in the shaft, pulley and disks. A pin 104 is mounted in the hole thus formed and is cut 15 away for half of its diameter where it passes through the pulley as shown at 105 in Fig. 8. An arm 106 is secured to the end of this pin by a small pin 107. A spring 108 secured to the end of the pin 107 and to the disk 102 20 tends to swing the arm toward the stop 109 thereby rotating the pin 104. When the arm is against the stop the pin 104 is turned so that it is half in the shaft and half in the pulley thus clutching the pulley to the shaft. 25 When the arm 106 is rotated about ninety degrees from the stop the semi-circular part of the pin 104 is positioned entirely in the groove in the shaft and the pulley is free to rotate. To move the arm to this position I 30 provide a rock shaft 110 mounted in brackets on the carriage and having its end bent to form a stop 111. This rock shaft can be rotated through a limited angle to raise the stop 111 to a position to engage the arm 106 during the rotation of the disk 102. When the stop engages the arm the pin 104 is rotated by the movement of the disk until the pulley is released from the shaft and rotates idly. When the stop is again depressed 40 the spring 108 is free to set and when the groove of the pulley comes opposite the groove of the shaft it will rotate the pin 104 to clutch the pulley to the shaft. A retaining bracket 112 secured to the disk prevents 45 the accidental outward movement of the pin 104.

The rock shaft 110 may be rotated by an arm 113 secured thereto and projecting to within easy reach of the operator and is retained in either position by a spring detent 114 engaging a projection 115 on the lever. To automatically disconnect the clutch I provide a depending arm 116 secured to the 50 rock shaft 110 and a stop 117 secured to the platform in such position that the rock shaft will be rotated to raise the stop 111 during the last feeding movement of the carriage. The main shaft continues to rotate for a part of a revolution insuring the release of the 55 ratchet mechanism 40, the release of the pawl 35 from the segment tooth 55, and the consequent return of the carriage. The rotation of the main shaft ceases while the needle bar is still in elevated position.

60 The operation of the device is as follows:

The adjustable stop 48 is set to correspond with the size of tag to be used. The merchandise with the tag in position is placed underneath the work clamping member and the lever 113 is depressed throwing in the 70 clutch to connect the stitch forming mechanism to the source of power. Upon the first downward thrust of the needle bar the clamping member is depressed automatically clamping the work to the work table. The 75 stitch forming mechanism sews the tag to the merchandise while the pawl 35, and the eccentric 36, automatically feeds the carriage. The last two stitches are formed in one hole through the yielding of the rack 80 segment. The spring plunger 80, engages the end of the lever 12, compressing the spring 82, until the pawl 77, is released during the last feeding movement of the carriage when the knife is forced forward and 85 cuts the thread. During this last feeding movement the arm 116, engages its stop rotating the rock shaft 110, to release the clutch 10, and the cam 44, moves the pawl 41, so that it is engaged by the retaining 90 latch 45. As the feed pawl 35, moves out of the engagement with the tooth 55, of the rack segment the carriage returns to initial position. As the carriage returns the cam 96, engages the projection 65, releasing the 95 detent 62, and permitting the rack segment to return to its initial position under the action of the spring 61. Also during the return movement of the carriage the cam 95, engages the projection 94, of the clamping 100 member thereby raising the clamping member and releasing the work. As the carriage strikes the stop 48, the pin 52, is moved inwardly releasing the pawl 41, and all the parts are restored to initial position. 105

I have described a preferred form of the apparatus but the invention in its broader principles is not limited to the apparatus shown.

While I have shown the stitch forming 110 mechanism as movable the essential requirement is that there shall be relative movement between the stitch forming mechanism and the work clamping member with means for stopping the operation of the stitch forming 115 mechanism and restoring the parts to initial position.

Various modifications may be made without departing from the spirit of the invention as defined by the claims. 120

Having fully described my invention what I claim as new and desire to secure by Letters Patent is;—

1. An automatic machine of the class described comprising a stitch forming mechanism and means for operating it, a work clamp having members adapted to grip the work positively and continuously during the stitch forming operation, means for causing a relative step by step feeding movement in 125 130

a substantially straight line for a predetermined distance between said stitch forming mechanism and said clamp, means for stopping the operation of the stitch forming mechanism at the termination of said feeding movement and for automatically restoring the stitch forming mechanism and clamp to initial position.

2. An automatic machine of the class described comprising a stitch forming mechanism, a work support, means operated in connection with said stitch forming mechanism for causing a relative feeding movement between the stitch forming mechanism and the work support in one direction along a predetermined path, means for stopping the operation of the stitch forming mechanism at the termination of said feeding movement and automatically returning the movable part through the same path to initial position.

3. A machine for sewing tags to merchandise comprising a stitch-forming mechanism, a work clamp, a source of power, driving connections between said source of power and said stitch-forming mechanism and means operated in unison with said stitch-forming mechanism for causing relative movement between said stitch-forming mechanism and work clamp step by step successively in one direction to form a row of stitches, with a dwell during the formation of each stitch and a continued dwell during the formation of two stitches near the end of said movement.

4. A machine for sewing tags to merchandise comprising a stitch-forming mechanism, a work clamp, a source of power, driving connections between said source of power and said stitch-forming mechanism means operated in unison with said stitch-forming mechanism for causing relative movements successively in one direction between the stitch-forming mechanism and the work clamp step by step to form a row of stitches with a dwell during the formation of each stitch and a continued dwell during the formation of two stitches near the end of said movement, means for automatically disconnecting the stitch-forming mechanism from the source of power at the termination of the relative movement and means for automatically returning the movable element to initial position.

5. An automatic machine of the class described, comprising a stitch forming mechanism, a stationary work clamp, a source of power, driving connections between said source of power and stitch forming mechanism, means for causing a feeding movement of said stitch forming mechanism relative to said stationary work clamp in one direction for a predetermined number of stitches, means for automatically disconnecting the stitch forming mechanism from said source

of power after said predetermined number of stitches, and means for automatically returning the stitch forming mechanism to initial position.

6. In an automatic machine of the class described in combination, a support, a stitch forming mechanism pivotally mounted on said support, a feeding mechanism for swinging said stitch forming mechanism about its pivot in one direction step by step for a predetermined number of consecutive stitches, a source of power, means for driving said stitch forming mechanism and feeding mechanism from said source of power, means for automatically disconnecting said feeding mechanism and said stitch forming mechanism from the source of power and returning said stitch forming mechanism to initial position.

7. In an automatic machine of the class described in combination a stitch forming mechanism, a work clamp, means for causing relative movement between the stitch forming mechanism and the work clamp step by step for a predetermined number of stitches in one direction, means for permitting automatic locking of the thread at the termination of the stitch forming operation and means for automatically cutting the thread after the stitch forming operation.

8. In an automatic machine of the class described in combination a stitch forming mechanism, a work clamp, means for causing a relative feeding movement between the stitch forming mechanism and the work clamp step by step for a predetermined number of stitches in one direction with a dwell during the formation of each stitch, means for automatically stopping the stitch forming mechanism at the termination of the feeding movement, means for permitting automatic locking of the thread at the termination of the stitch forming operation, means for automatically cutting the thread after the locking of the thread and means for automatically restoring the parts to initial position.

9. In an automatic machine of the class described in combination a stitch forming mechanism, a work clamp to grip and hold the work, means for causing a relative movement between the stitch forming mechanism and the work clamp step by step for a predetermined distance in a predetermined path with a dwell during the formation of each stitch, means for automatically stopping the stitch forming mechanism at a predetermined point, means for automatically returning the movable mechanism to initial position in the same path and means actuated by said movable mechanism on its return movement for automatically releasing the work.

10. In an automatic machine of the class described in combination a support, a stitch

- forming mechanism movably mounted upon said support, a work clamp mounted upon said support and feed mechanism for moving said stitch forming mechanism comprising a pawl carried and operated by said stitch forming mechanism, a rack secured to the support and positioned to be engaged by said pawl, a second rack secured to said support and a spring pressed pawl movable with said stitch forming mechanism and adapted to hold said stitch forming mechanism in definite positions relative to said support.
11. In an automatic machine of the class described, in combination a support, a carriage pivotally mounted on said support, a feed mechanism for moving said carriage relatively to said support comprising a rack secured to said support, a pawl engaging said rack and operable to move said carriage intermittently and a movable element positioned at one end of said rack and having two teeth and arranged to move under the influence of said pawl when one tooth is engaged by said pawl and to remain stationary when the other tooth is engaged by said pawl thereby causing the carriage to be moved when said other tooth is engaged by said movable pawl.
12. In an automatic machine of the class described in combination a support, a stitch forming mechanism mounted on said support, a work clamp also mounted on said support, means for causing a relative feeding movement between said stitch forming mechanism and the work clamp step by step for a predetermined distance in one direction and a knife movably mounted on said support and means set in operation by the relative step by step feeding movement of said stitch forming mechanism and work clamp for moving said knife to cut the thread at the end of the stitch forming operation.
13. An automatic machine of the class described comprising a stitch forming mechanism and means for operating it, a work clamp, means for causing a relative step by step feeding movement for a predetermined distance between said stitch forming mechanism and said clamp, means for stopping the operation of the stitch forming mechanism at the termination of said feeding movement and for automatically restoring the stitch forming mechanism and clamp to initial position by returning the movable element through the same path of movement, and means adjustable to determine the amount of relative movement.
14. An automatic machine of the class described comprising a support, a carriage pivotally mounted on said support, a stitch forming mechanism mounted on said carriage a work clamp connected to said support and arranged to hold the work in fixed
- position to be operated upon by said stitch forming mechanism, a carriage controlling mechanism arranged to give said carriage a forward feeding movement step by step for a predetermined distance and a continuous 70 backward return movement to initial position.
15. An automatic machine of the class described comprising a support, a carriage pivotally mounted on said support, a stitch 75 forming mechanism mounted on said carriage, a work clamp connected to said support and arranged to hold the work in position to be operated upon by said stitch forming mechanism, a feeding mechanism comprising a rack and pawl and a yieldable toothed member at one end of said rack operable to give said carriage a forward feeding movement step by step for a predetermined distance with a dwell during the 85 formation of each stitch and a continuous dwell during the formation of two stitches and means for causing said feeding mechanism to cease operation and means for giving said carriage a continuous return movement. 90
16. A machine of the class described comprising a stitch forming mechanism, a work support, a feeding mechanism comprising a rack secured to the work support and a 95 pawl carried by the stitch-forming mechanism, and means for causing a dwell in the operation of said feeding mechanism such that two stitches will be formed in the same place in the work thereby tying a knot in 100 the thread.
17. A sewing machine comprising a stitch forming mechanism, a work support, means for causing a relative feeding movement between said mechanism and said support comprising a rack secured to the work support and a pawl carried by the stitch-forming mechanism, and means for causing at a predetermined time a dwell in the action of said feeding means during the formation of 110 two successive stitches whereby the thread is fastened.
18. In an automatic machine of the character described, a support, a carriage pivotally connected to said support, a stitch-forming mechanism carried by said carriage and a rack and pawl mechanism for giving a step by step feeding movement to said carriage with a dwell during the formation of 115 each stitch. 120
19. In a machine of the character described comprising work clamping mechanism and stitch forming mechanism, means for causing step by step movement between the work clamping mechanism and the stitch forming mechanism comprising a rack connected to the work support, a co-operating pawl carried by the stitch forming mechanism and means for actuating the same, means carried by said stitch forming mecha- 125 130

- nism adapted to prevent a return movement of the carriage during the stitch forming operation and means for releasing the latter at the termination of the stitch forming operation to permit the return of said mechanism to initial position comprising a co-operating rack and dog and means for holding said dog retracted during the return movement.
20. In a machine of the character described comprising work clamping mechanism and stitch forming mechanism, means for causing step by step movement between the work clamping mechanism and the stitch forming mechanism comprising a rack connected to the work support, a co-operating pawl carried by the stitch forming mechanism and means for actuating the same, means carried by said stitch forming mechanism adapted to prevent a return movement of the carriage during the stitch forming operation and means for releasing the latter at the termination of the stitch forming operation to permit the return of said mechanism to initial position comprising a co-operating rack and dog, means for holding said dog retracted during the return movement, and means for releasing said dog when the mechanisms have reached initial position.
21. In a machine of the character described comprising a work clamping mechanism and means for causing relative step by step movement between said work clamping mechanism and the stitch forming mechanism to produce a predetermined number of stitches, means for restoring the stitch forming mechanism and work clamping mechanism to initial position, means automatically operated during said restoring movement for cutting the thread and means also operated during the restoring movement for releasing the work clamping mechanism.
22. In a machine of the class described comprising a work support, stitch forming mechanism pivotally mounted thereupon and means for causing relative step by step movement between said work support and stitch forming mechanism, a clamp pivotally mounted on said work support adapted in co-operation therewith to grip the work and means operating upon the return movement of the stitch forming mechanism to release said clamp from the work.
23. In a machine of the class described comprising a work support, stitch forming mechanism pivotally mounted thereupon and means for causing relative step by step movement between said work support and stitch forming mechanism, a clamp pivotally mounted on said work support adapted in co-operation therewith to grip the work and means operating upon the return movement of the stitch forming mechanism to release said clamp from the work.
24. In a machine of the class described comprising a work support, stitch forming mechanism pivotally mounted thereupon and means for causing relative step by step movement between said work support and stitch forming mechanism, a clamp pivotally mounted on said work support adapted in co-operation therewith to grip the work and means operating upon the return movement of the stitch forming mechanism to release said clamp from the work comprising a cam engaging an extension upon said work clamp.
25. In a machine of the character described comprising a work support and stitch forming mechanism, means for causing relative step by step movement between the said work support and stitch forming mechanism, a work clamp pivotally mounted on said work support, a spring attached to said work support and to said clamp adapted to lie upon one side of said pivot when the clamp is in clamping position and thereby to retain it in engagement with the work and adapted to lie upon the opposite side of said pivot when the clamp is raised from work engaging position and thereby to support said clamp in elevated position.
26. In a machine of the character described comprising a work support and stitch forming mechanism, means for causing a relative movement between said work support and said stitch forming mechanism, a clamp pivotally mounted upon said work support and co-operating therewith to grip the work, an extension beyond the pivot of said clamp, a spring attached to said clamp and to said work support and adapted to be positioned upon either side of said pivot and means carried by the stitch forming mechanism adapted to depress said extension and thereby raise the clamp and shift the spring from one side of said pivot to the other to raise the clamp from gripping position and to maintain the same in raised position.
- In testimony whereof, I have signed my name to this specification, in the presence of two subscribing witnesses.
- MARCUS O. ANTHONY.
- Witnesses:
- HENRY POLK,
C. ALBIN WALLIN.
